UNITED STATES PATENT OFFICE.

GEORGE C. TATE, JR., OF MALDEN, MASSACHUSETTS.

WIRE PICTURE-CORD.

SPECIFICATION forming part of Letters Patent No. 352,499, dated November 9, 1886.

Application filed February 24, 1886. Serial No. 193,096. (No model.)

To all whom it may concern:

Be it known that I, GEORGE C. TATE, Jr., of Malden, in the county of Middlesex and State of Massachusetts, have invented certain 5 new and useful Improvements in Wire Picture-Cords, of which the following is a specification.

My invention relates to picture-cords, and particularly to that class of such articles composed of a plurality of wires plaited or braided together to form the cord, the object of the invention being to so improve a wire picture-cord of the character mentioned that it will not stretch when subjected to tensile strain, occasioned by hanging a picture or analogous article thereto, or be weakened by use or age, occasioned by the decay or disintegration of any of the component parts.

My invention consists in an improved non-extensible wire picture-cord composed of a straight flexible wire core having a plurality of wires plaited or braided therearound in such manner as to give "body" to the cord and aid in sustaining any tensile strain to which the 25 cord may be subjected, all as hereinafter fully described, and subsequently pointed out in the claims.

In the drawings hereto annexed and forming a part of this specification, Figure 1 represents on an exaggerated scale a portion of my wire picture-cord formed in the way that I prefer to construct it. Fig. 2 is a cross-section thereof on the line $x x$, Fig. 1.

The same letters of reference refer to the 35 same parts in both figures.

a represents the core of my cord, which core is composed of comparatively soft or yielding metal, so that it can be readily bent, and around this core I plait or braid a number of wires, *b*, 40 preferably smaller or of finer gage than the core *a*, in such manner as to cover the straight core and give body to the cord, and at the same time aid it in sustaining any tensile strain to which it may be subjected when a picture 45 or analogous article is hung thereto, as is clearly represented in the drawings. I show nine strands of wire *b* as plaited around the core *a*, though a greater or less number of such wires may be employed, according to the character and size of the picture-cord it is desired 50 to form.

Wire picture-cord as heretofore constructed has usually been composed of a number of small strands of wire braided or plaited together, as my improved cord would be without the straight core *a*, and while the requisite strength and flexibility of the cord are thus secured, it is open to the objection that it gradually stretches when a picture of any considerable weight is hung thereto, and the picture 55 is thus thrown out of place or position. By my invention this difficulty is overcome, a cord being provided that will not stretch under the circumstances mentioned, and will yet be as flexible and as easily bent as wire cords of ordinary or common construction. Besides this, the wires *b*, braided or plaited around the core *a*, give body or size to the cord, enhancing its appearance, and by being braided or plaited around the core at a slight angle to its 60 length receive a portion of the tensile strain to which the cord is subjected when in use, and so strengthen the same.

I am aware that a picture or sash-cord has heretofore been constructed composed of a 75 steel wire or core of required resistance to tensile strain, around which was wound an ornamental wire and a waxed thread in close spiral coils, or a spiral of small pitch, so that the covering wire and thread should not bear any 80 of the strain to which the cord might be subjected.

I am also aware that a picture-cord has heretofore been manufactured consisting of a body of several strands or a single strand provided 85 with a fibrous wrapping and having an outer wrapping or covering of wires braided thereon. Neither of these cords, however, is composed wholly of wire, as is my cord; but both contain fibrous material in their structure, which 90 prevents them from being dipped in acid to cleanse them for the purpose of plaiting and for other reasons, as is necessary after the wires have been formed into a cord. Again, neither of the cords just referred to is as 95 flexible as my improved cord—a very desirable feature in the construction of picture-cords. Furthermore, my improved cord can be easily and cheaply manufactured, and by reason of the fact that it can be plaited to keep it 100 from corroding and be cleansed at any time by washing it with acid or any other liquid,

there being no fibrous material in its composition to be destroyed or to decay, it maintains its strength and appearance for substantially an indefinite period.

5 What I claim is—

1. An entirely metallic picture-cord consisting of a core of straight wire having a plurality of wires plaited or braided therearound at a slight angle thereto, to aid in sustaining any tensile strain to which the cord may be subjected when in use, as set forth.
2. An entirely metallic picture-cord consist-

ing of a core of straight wire having a plurality of wires of finer gage than the core plaited or braided therearound, as set forth.

In testimony whereof I have signed my name to this specification, in the presence of two subscribing witnesses, this 14th day of January, 1886.

GEORGE C. TATE, JR.
